UNITED STATES PATENT OFFICE.

JESSE HARRIS, OF LA FAYETTE, INDIANA, ASSIGNOR TO DUNCAN ELECTRIC MANUFACTURING COMPANY, OF LA FAYETTE, INDIANA, A CORPORATION OF ILLINOIS.

TOTALIZING MECHANISM.

Application filed August 12, 1928. Serial No. 128,845.

My invention relates to totalizing mechanisms employing indexes, such as pointers having dials around which the pointers travel, totalizing mechanisms of this character being 5 in common use as, for example, in connection with watt hour electricity meters.

In order to restore the indexes or pointers of such a totalizing mechanism to zero positions, it was hitherto possible either to dismount the totalizing mechanism in order to uncouple it from the motive element of the meter to permit free but slow restoring movement of the pointers, or to force each pointer, if frictionally held, back to zero position. By 15 means of my invention, the pointers of the totalizing mechanism may be readily restored to zero positions by operating the gearing and preferably without dismounting the totalizing mechanism. To this end, I employ 20 adjusting means for unmeshing some of the gears through which motion is transmitted to the pointers or some of the pointers whereby the gears that remain in control of such pointers may be easily rotated in forward or 25 reverse directions merely by grasping and turning one of the pointers which is turned until all of such pointers are brought to zero positions.

I will explain my invention more fully by 30 reference to the accompanying drawing in which Fig. 1 is a front view of a totalizing mechanism equipped with the device of my invention; Fig. 2 is a sectional view on line 2-2 of Fig. 1; Fig. 3 is similar to a part of 35 Fig. 2 but with two of the gears unmeshed; and Fig. 4 is a rear view illustrating the unmeshing of the gears, parts being broken away.

The totalizing mechanism illustrated is one 40 that is employed in electricity watt hour meters. I have illustrated the upright spindle 1 of such a meter and a portion 2 of the metallic meter disc. A worm 3 is provided upon the spindle which is constantly in mesh 45 with a worm wheel 4 fixed upon a horizontal shaft 5. An arm 6 is fixed upon the shaft 5 and extends radially therefrom into the plane of rotation of the angular extension of an arm 7 which is secured to the horizontal shaft 50 8 of the totalizing mechanism. This shaft is journaled upon two parallel plates 9 and 10. A small gear wheel or pinion 11 is fixed upon the shaft 8 and is in mesh with a larger gear wheel 12 which is fixed upon a shaft 13 55 that is journaled in said plates 9 and 10. A

small gear wheel or pinion 14 is fixed upon the shaft 13 and is in mesh with a larger gear wheel 15 fixed upon a shaft 16 which is also journaled in the plates 9 and 10. A small gear wheel or pinion 17 is fixed upon the shaft 16 and is in mesh with a larger gear wheel 18. The gear wheel 18 is fixed upon the shaft 19 which is journaled at its front end in a plate 20 which is parallel with the plates 9 and 10, this shaft passing through an opening in the plate 10. The rear end of this shaft is journaled in a bearing 21 which is carried by the plate 9. The remaining gear wheels are disposed between the plates 10 and 20. A small gear wheel or pinion 22 is fixed upon the shaft 19 and is in mesh with a larger gear wheel 23 which is fixed upon a shaft 24 that is journaled in the plates 10 and 20. A small gear wheel or pinion 25 is fixed upon the shaft 24 and is in mesh with a larger gear wheel 26. The latter gear wheel is fixed upon a shaft 27 which is journaled in the plates 10 and 20. A small gear wheel or pinion 28 is fixed upon the shaft 27 and is in mesh with a larger gear wheel 29 which is fixed upon a shaft 30. The latter shaft is journaled in the plates 10 and 20.

The shafts 19, 24, 27 and 30 have reduced ends that project through the front plate 20. Indexes or pointers 31, 32, 33 and 34 are 85 respectively provided upon the front ends of said shafts, each pointer desirably having a hub portion which has tight frictional fit with the corresponding shaft. Dials 35, 36, 37 and 38 are respectively individual to 90 said pointers and have circular rows of characters respectively concentric with the shafts carrying the pointers.

Motion that is imparted to the arm 7 by the arm 6 is transmitted at suitably reduced speed through the speed reducing gearing 11, 12, 14, 15 and 17 to the gear wheel 18 and the pinion 22 fixed with respect to and coaxial with this gear wheel and forming with said gear wheel an initial one of three sets 100 of gear wheels arranged in succession, the second set comprising the gear wheels 23 and 25 and the third set comprising the gear wheels 26 and 28. In order that all of the pointers may be brought to zero positions merely by turning one of them, the train of gears is broken that includes the speed reducing gearing 11, 12, 14, 15 and 17 and the large gear wheel 18 of the aforesaid initial set of gear wheels. To this end, one of these gear wheels, 110

- preferably the gear wheel 18, is provided with means for unmeshing it from the next preceding gear of the speed reducing gearing in order that the gears 18 and 22 and all of 5 the succeeding gears may be freely rotated without being hindered by the speed reducing gearing and without being prevented from being so rotated by the arm 6 of the meter. To this end, the rear end of the shaft 10 19 is journaled in the bearing 21 eccentrically to this bearing. The bearing is shown as being screwed into the plate 9 and as having an arm 39 in fixed connection with the rear end of the bearing so that the bearing may 15 be turned upon its own axis to shift the position of the inner end of the shaft 19. When the gear wheel 18 is in mesh, its axis and the axis of bearing 21 are substantially parallel. When the pointers are to be restored to normal, the arm 39 is desirably turned sufficiently to unmesh the gear wheel 18 from the pinion 17 while the pinion 22 is still in mesh with the gear wheel 23. When this adjustment has been effected, one of the pointers, 20 25 preferably pointer 32 or 33, is turned until

all of the pointers are brought to zero positions.

Changes may be made without departing from the invention.

Having thus described my invention, I 30 claim:

Totalizing mechanism including motion transmitting speed reducing gearing; a gear wheel in mesh with the final gear of said speed reducing gearing; an index upon the 35 shaft of said gear wheel; and a bearing for said shaft and mounted to turn upon its own axis and upon which bearing this shaft is journaled eccentrically to the axis of the bearing, said bearing and said gear wheel 40 being relatively disposed to enable said gear wheel to be thrown out of connection with the aforesaid reducing gearing by suitably turning the aforesaid bearing, the axes of said bearing and gear wheel being substantially parallel when said gear wheel is in mesh.

In witness whereof, I hereunto subscribe my name.

JESSE HARRIS.
